Primary Examiner — Janice Hallmark(74) *Attorney, Agent, or Firm* — McGarry Bair PC(57) **CLAIM**

The ornamental design for a ceiling fan motor housing, as shown and described.

DESCRIPTION

FIG. 1 is a top perspective view of a ceiling fan motor housing shown in the environment of a ceiling fan, showing my new design;

FIG. 2 is a bottom perspective view of the ceiling fan motor housing of FIG. 1 having the ceiling fan environment removed;

FIG. 3 is a top view thereof;

FIG. 4 is a bottom view thereof; and,

FIG. 5 is a side view thereof.

Portions of the ceiling fan motor housing and the ceiling fan environment are shown in broken lines. Portions shown in broken lines form no part of the claimed design.
